UNITED STATES PATENT OFFICE.

LOUIS DAMARIN GREGG, OF HACKENSACK, NEW JERSEY, ASSIGNOR TO THE GREGG COMPANY, LIMITED, OF HACKENSACK, NEW JERSEY, A CORPORATION OF NEW YORK.

STAKE-POCKET.

1,145,479.

Specification of Letters Patent.

Patented July 6, 1915.

Application filed November 5, 1914. Serial No. 870,457.

To all whom it may concern:

Be it known that I, LOUIS DAMARIN GREGG, a citizen of the United States, residing at Hackensack, in the county of Bergen and State of New Jersey, have invented certain new and useful Improvements in Stake-Pockets; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to stake-pockets for securing stakes to cars, and particularly to that type in which is embodied a swinging door to a pocket, the door being capable of being lifted and swung to one side when 20 the pocket is to be opened, and not requiring any extraneous or locking devices for holding it when in its closed position.

The object of the present invention is to 25 provide improved features of construction in a stake-pocket of the type mentioned by which the door can be more readily lifted when being opened and without binding on the hinging pin or at any time throwing such stress on the pin as might tend to bend 30 or deflect the same and thus make it more difficult to manipulate the door. Also in which a fulcrum for the hinged door will be provided at the rear of the hinging pin, and in which also the free end of the door 35 can be released from the holding nose or keeper of the pocket without the necessity of lifting the door to the same extent as would otherwise be the case.

40 To the accomplishment of the foregoing and such other objects as may hereinafter appear the invention consists in the features hereinafter particularly described and then sought to be particularly pointed out in the claims, reference being had to the accompanying drawing forming a part hereof, and in which:—

Figure 1 is a front elevation of a stake-pocket embodying my invention; Fig. 2 is a top plan view of the same; Fig. 3 is a 50 vertical section on the line 3—3 of Fig. 2, with the door lifted and ready to be swung open; Fig. 4 is a vertical section through a portion of the pocket and door, with the door in its closed position, and illustrating

a spring that may encircle the hinging pin 55 or pintle.

In the drawing the numeral 1 designates the body-portion of the pocket which may be of any appropriate design but is preferably of the form illustrated, and has at one point a nose or keeper 2 to receive the free end of the door 3, and at another point has a bolt or pintle 4 to receive the butt-end of the door and serve as a pintle for the door to swing upon. The butt-end of the door is formed with an internal cavity 5 elongated in the direction of the length of the door and through which the pintle 4 passes, the top edge of the sides of the butt inclining downwardly in a forward direction. The shoulder 6 at the rear of the door sets back from the edge of the upper ear 7, and the door is undercut at 8 so as to permit the shoulder 6 to ride above the ear 7 when the door is raised as shown in Fig. 3 75 preparatory to being swung outwardly. The door in its lowermost or closed position appears as in Figs. 1 and 4, with the under face or bottom of its butt resting on the lowermost ear 9 of the body portion as seen 80 in Figs. 1 and 4, said ear, at the rear of the pintle, serving as the fulcrum for the door in lifting the latter as indicated in Figs. 3 and 4, thus facilitating the lifting of the door and taking practically all stress from 85 off the pintle. The under face of the door is formed with a wedge-shaped recess 10 the base of which will lie substantially parallel with the top face of the socket-keeper 2 when the door is raised to the position 90 shown in Fig. 3 so that the door may then be swung outward for the release of the stake. By forming this recess the door may be given more depth of metal at its rear portion for increased strength, and the necessity of lifting the door higher in order 95 to clear the socket-keeper is obviated.

It is preferred to form a bead 12 around the top edge of the butt to give additional strength and to extend this bead upward to 100 form a flange 13 at the forward end of the butt, on the outer face thereof, as shown in Fig. 1, and also to form a boss 14 at the lower portion of the butt as shown in Figs. 1, 3 and 4, for increased strength, but these 105 preferred details may be omitted. It is also preferred to have a coiled spring 15 to encircle the pintle 4 as shown in Fig. 4, so

as to exert a downward spring pressure on the door but this is not essential and may be omitted. Under this construction lightness without sacrifice of strength is obtained, and greater ease and facility in operating the door is attained, and any undue stress and deflection of the pintle and binding or cramping of the parts in operation is prevented.

10 I have illustrated and described the preferred details of construction of the several parts but changes can be made therein without departing from the scope of the invention as expressed in the appended claims.

15 Having described my invention and set forth its merits, what I claim is:—

1. A stake-pocket having a hinged door capable of tilting vertically and swinging transversely in opening and closing, and
20 means for supporting the door in a substantially horizontally extended position when open.

2. A stake-pocket having a swinging door formed with a tapering socket in its butt to receive a pintle and permit the door to swing on the pintle and to tilt in relation thereto.

3. A stake-pocket having a door, a keeper for its free end, and a pintle hinging the door, the butt of the door having a socket for the pintle of sufficiently greater diameter than the pintle to permit the door to move or tilt vertically in engaging the keeper and also to swing transversely of the axis of the
35 pintle.

4. A stake-pocket having a swinging and vertically tiltable door, the door and a portion of the pocket at the free end of the door formed to interlock one with the other, and
40 means for supporting the door in a substantially horizontally extended position when open.

Copies of this patent may be obtained for five cents each, by addressing the "Commissioner of Patents, Washington, D. C."

5. A stake-pocket having a tiltable and hinged door formed at its rear with a butt-socket to receive a pintle, the lower portion 45 of the butt at the rear of the pintle resting upon a fulcrum and the wall of the socket in front of the pintle being normally spaced from the pintle and movable toward the pintle when the door is raised.

6. A stake-pocket having a tiltable and hinged door formed with a butt-socket to receive a pintle, the interior of the socket being elongated in the direction of the length of the door, the rear of the door at 55 the front of the socket being spaced from the upper bearing for the pintle and formed with an undercut portion, to permit the rear of the door to ride above the upper bearing of the pintle.

7. A stake-pocket having a tiltable and hinged door formed with a butt-socket to receive a pintle, the wall of the socket in front of the pintle being normally spaced 65 from the pintle and movable toward the pintle when the door is raised, and the portion of the door at the top of the socket being spaced from the upper bearing of the pintle to permit the door to ride above the
70 pintle-bearing.

8. A stake-pocket having a tiltable and hinged door formed with a butt-socket to receive a pintle upon which the door may swing horizontally, and a keeper to receive the forward portion of the door, the door being formed in its lower face with a recess 75 to permit the door to swing over the face of the keeper when the door is raised.

In testimony whereof I affix my signature in presence of two witnesses.

LOUIS DAMARIN GREGG.
